UNITED STATES PATENT OFFICE.

JOHN O. CARREY, OF ST. LOUIS, MISSOURI, ASSIGNOR TO CARREY-MORSE ENGINEERING COMPANY, OF ST. LOUIS, MISSOURI, A CORPORATION OF MISSOURI.

THERMOSTAT.

Application filed May 1, 1925. Serial No. 27,261.

This invention relates to new and useful improvements in thermostats, the primary object being to provide a thermostatic device for positively operating an electric switch in 5 a predetermined relation with the temperature.

Further objects of the invention are to provide a thermostat which is of strong and durable construction, is sensitive in operation, and is sufficiently powerful to successfully operate the device with which it is associated.

Other objects of the invention are to provide simple means for regulating said thermostatic device to render it operative at certain temperatures. The invention briefly consists of two thermostatic elements of dissimilar materials having unequal coefficients of expansion and suitable switch mechanism 20 operable by one of said elements. One of the elements forms a support or casing in which is arranged the other one of said elements, the latter having opposed operating or pivot points which engage and operate a 25 lever associated with the switch mechanism. The support element has greater coefficient of expansion and consequently causes the points of the other elements to move to and from each other in accordance with the 30 temperature which causes the expansion and contraction of said support element. The switch mechanism preferably includes snap action means for insuring quick make and break contact.

With these and other objects in view, my invention consists in certain novel features of construction and arrangement of parts, hereinafter more fully described and claimed, and illustrated in the accompanying drawings, in which—

Figure 1 is a top plan view of the device with the cover removed.

Figure 2 is a vertical cross section taken through the device.

Figure 3 is a fragmental plan view of the device showing the same in moved position.

Figure 4 is a detail view taken on line 4—4 of Figure 1.

Figure 5 is a top plan view of a modified form of my improved thermostat with the cover thereof removed.

Figure 6 is a vertical cross section taken longitudinally through the device.

Figure 7 is a top plan view of the mechanism and showing the same in moved position.

Referring by numerals to the accompanying drawings, 10 indicates a circular casing, preferably made of metal, such as zinc, which has a comparatively high coefficient 55 of expansion. This casing comprises a bottom wall 11 and an annular wall 12 formed integral with said bottom wall and provided with an enlarged annulus 14 which is internally threaded and forms an annular 60 shoulder 15. A cover 16 made of the same metal as the casing is provided with a circular rib 17 externally threaded for engagement with the threaded portion 14. A resilient split ring 18, preferably formed of 65 steel or other material having comparatively low coefficient of expansion is placed in casing 10 in a close fit with annular wall 12. The ends 19 of this ring are preferably 70 tapered to form knife-edge points 20 which are offset relative to each other in radial direction. The coefficient of expansion of ring 18 is considerably less than that of the casing 10 and consequently when the latter contracts, due to the change in temperature, 75 the annular wall 12 of said casing encircling ring 18 will cause the latter to contract, bringing the points 20 thereof toward each other. Conversely, when casing 10 expands the annular wall 12 expands outwardly and 80 the resiliency of ring 18 will cause the latter to expand, thereby moving points 20 away from each other. This relative movement 85 of points 20 is taken advantage of to operate suitable switch mechanism by means of a 90 lever 21, one end 22 of which is provided with oppositely disposed seats 24, preferably V-shaped for receiving the knife-edge points 20.

Connected to lever 21 as indicated at 95 one end of an arm or link 26, the opposite end of which is formed with a slot 27 for engaging an upstanding pin 28. This pin projects upwardly from an arm 29 of a member 30 which is loosely mounted for 100 pivotal movement on the lower end of a pin 31 which is fixed to the bottom wall 11 of casing 10. Pivotedly mounted on the upper end of pin 31 is one end of an arm 32, the opposite end of which carries a contact blade 105 34, which is adapted to engage either one

of oppositely disposed contact members 35 and 36, respectively, fixed to the bottom wall of casing 10.

Member 30 is provided with a pair of upwardly presented lugs 30^a arranged on each side of arm 32 and spaced therefrom. An adjusting screw 37 is screw-seated in the threaded aperture of each lug and has its end presented inwardly for engaging the respective side of arm 30. The distance between the operating points of screws 37 is greater than the width of arm 32, thereby providing lost motion for member 30 relative to arm 32. This distance can be regulated by adjusting screws 37 in order to effect operation of arm 32 at the desired moment.

A coiled spring 38 is connected at one end to a pin 39 which is carried by arm 32 and is located on the center line thereof and the opposite end of said spring is connected to a pin 40 which is seated in the bottom wall of casing 10 and is arranged in line with pin 39 and the pivotal axis of arm 32 when the latter occupies central or neutral position with respect to contacts 35 and 36. In this manner, spring 38 constitutes a snap action means for quickly bringing arm 32 to any one of its extreme positions as soon as said arm passes its center.

Arm 21 is operated in the direction indicated in Figure 1, which is the "cold" position, by the contraction of circular wall 12 which causes the split ring 18 to move inwardly, thereby bringing the points 20 thereof toward each other and rocking lever 21 in the direction indicated by the arrow in Figure 1. When the circular wall 12 expands, due to the rise in the temperature, ring 18 expands accordingly, causing the ends thereof to move away from each other, whereupon lever 21 is moved in the opposite direction to a position shown in Figure 3. This movement is effected by means of a coiled spring 41 one end of which is connected to lever 21 and the opposite end of which is anchored to a pin 42 which is fixed to and projects from the bottom wall 11 of casing 10. Link 26 is pivotally connected to lever 21 but this pivotal connection is rendered rigid by means of adjusting screws 45 which are screw-seated in lugs 46 laterally projecting from link 26 adjacent to lever 21. Screws 45 can be adjusted to vary the relative positions of lever 21 and link 26 in order that lever 21 can be operated at predetermined temperatures as indicated by a chart 47 which is fixed to the bottom wall 11 and with which cooperates a pointer 48 projecting from lever 21.

A flexible electrical connection 48 is connected to contact blade 34 and contact members 35 and 36 have connected thereto electrical connections 49 and 50, respectively.

65 These connections are connected to the elec-

trical circuits or apparatus which it is desired to control or which are used to operate suitable mechanism.

In the operation of my device, assuming that the thermostat is used in conjunction with a solenoid switch, such as disclosed in my copending application Serial Number 27,903, filed May 4, 1925, for controlling a refrigerating apparatus, connection 50 is connected to that terminal of the switch which sets the electric motor in operation and connection 49 is connected to that terminal which disconnects the motor circuit. With the arm 32 in the position shown in Figure 1, which is the "cold" position, the motor circuit of the refrigerating apparatus is disabled through the interengagement of contact blade 34 with contact 35, thereby rendering the refrigerating apparatus inoperative. This condition will continue until the temperature of the apparatus rises above a predetermined degree, whereupon the expansion of casing 10 will release the points 20 of ring 18 sufficiently to allow lever 21 to move to the position shown in Figure 3 in which position contact blade 34 engages contact 36 which establishes the motor circuit and sets in operation the refrigerating apparatus driven thereby. The position of arm 32 will remain unchanged, until the operation of the refrigerating apparatus brings the temperature thereof low enough to cause contraction of element 10 and the subsequent operation of lever 21 by points 20 of ring 18.

The interrelation of elements 10 and 18 are such that lever 21 is not operated immediately the change in temperature occurs, but a certain range, say of five degrees, is provided before the operation of lever 21 takes place. When lever 21 is operated, member 30 is rocked on its pivot, thereby bringing the corresponding screw 37 against arm 32 causing the latter to move in the appropriate direction. As soon as arm 32 passes the center line as indicated by x-x in Figure 1, spring 38 imparts snap action to said arm causing it to quickly complete its movement, screws 37 being used only to operate arm 32 during the first half of its movement.

In the form shown in Figures 5 to 7, inclusive, a box-shape casing 51 is used and one side thereof is provided with longitudinally disposed bores 52 which receive a pair of rods 54 having pointed ends 55 which are offset relative to the axes thereof. The opposite or outer ends of rods 54 bear against screw plugs 56 which are screw-seated in the enlarged threaded portions 57 of bores 52. Casing 51 is formed of material having a high coefficient of expansion, such as zinc, while rods 54 are formed of material having a comparatively low coefficient of expansion so that during the contraction of casing 51, points 55 of rods 54 are caused to move toward

each other. These points 55 operatively engage one end of a lever 58, the opposite end of which is engaged by the oppositely disposed screws 59 carried by member 60 which is pivotally mounted at 61 in casing 51 and is provided with upwardly presented lugs 62 disposed on each side of an arm 64 and carrying adjusting screws 65 for engaging said arm. This arm is pivotally mounted at 61 and carries at its opposite end a contact blade 66 which is adapted to engage either one of stationary contact members 67 and 68. A spring 69 connected at one end to arm 64 and anchored at the opposite end to the casing is used to impart snap action to said arm. Lever 58 is operated in one direction by the rearward movement of points 55 caused by the contraction of casing 51 and said lever is operated in the opposite direction by a tension spring 70 connected at one end to said lever and at the opposite end to a pin 71 which is fixed to the casing.

The operation of this device is similar to the device previously described and shown in Figures 1 to 4.

The screws 56 force rods 54 inwardly during the contraction of casing 51 and spring 69 causes said rods to move outwardly when the pressure against said rods is removed by expansion of casing 51.

The wearing surfaces of the thermostatic elements are lubricated by suitable lubricant, preferably by one which is not affected by extreme temperatures.

A thermostat constructed according to my invention is simple and positive in operation and is of durable construction as the thermostatic elements can be made sufficiently strong to furnish the necessary power for operating the switch or other mechanism.

While I have shown and described a preferred form of my invention, it is obvious that changes in the construction and arrangement of parts of my device can be made without departing from the spirit of my invention.

I claim:

1. A thermostatic device comprising in combination, a circular housing provided with an annular wall, a resilient split ring arranged within said housing and bearing against the inner face of said wall, the ends of said ring being offset in radial direction relative to each other, said housing and said ring having different coefficients of contraction and expansion whereby the contraction of said housing causes the ends of said ring to move toward each other, a lever arranged in said housing and having one end in fulcrum relation with said ends, being operable by said ends in one direction by the contraction of said housing, a tension member for moving the lever in the opposite direction, a stationary contact member, a switch blade pivotally mounted in said housing and movable into engagement with said contact member, an element connected to said lever, means for adjusting the relative positions of said lever and said element to render said lever operable at different temperatures, and a member having lost motion connection with said switch blade and in operative engagement with said element.

2. A thermostatic device comprising in combination, a circular housing provided with an annular wall, a resilient split ring arranged within said housing and bearing against the inner face of said wall, the ends of said ring being offset in radial direction relative to each other, said housing and said ring having different coefficients of expansion and contraction whereby the contraction of said housing causes the ends of said ring to move inwardly toward each other, a lever arranged in said housing and having one end in fulcrum relation with said ends, being operable in one direction by said ring by the contraction of said housing, a tension member for moving the lever in the opposite direction, a stationary contact member, a switch blade pivotally mounted in said housing and movable into engagement with said contact member, an element pivotally connected at one end to said lever, means carried by said element and engaging said lever at points disposed on each side of said pivotal connection of said element and said lever, said means being adjustable to vary the position of the lever and render it operable at different temperatures, a member having lost motion connection with said switch blade and operable by the opposite end of said element, and a spring for imparting snap action to said switch blade.

3. A thermostatic device comprising in combination, a housing of metal having a high coefficient of expansion, said housing being provided with an integral circular wall, a resilient split ring arranged within said housing and bearing against the inner face of said wall, said ring having a comparatively low coefficient of expansion whereby the ends of said ring are caused to move relative to each other in accordance with the expansion and contraction of said housing, a lever arranged in said housing and in operative engagement with the ends of said ring, the latter being offset relative to each other to form cooperating oppositely disposed fulcrums for said lever, a coiled spring having one end fixed and the opposite end connected to said lever for moving said lever in one direction, said split ring being adapted to move said lever in opposite direction, a stationary contact member, a switch blade pivotally mounted in said housing and movable into and out of engagement with said contact member, a plate pivotally mounted in said housing coaxially with said

- switch blade members carried by said plate and disposed on each side of said switch blade and adapted to engage the latter when said plate is actuated, an element fixedly connected to said lever at one end and having a pin and slot connection with said plate for actuating through said members said blade, and a coiled spring connected to said switch blade and to a fixed point for imparting snap action thereto.
4. A thermostatic device comprising in combination, a housing of metal having a high coefficient of expansion, said housing being provided with an integral circular wall, a resilient split ring arranged within said housing and bearing against the inner face of said wall, said ring having a comparatively low coefficient of expansion whereby the ends of said ring are caused to move relative to each other in accordance with the expansion and contraction of said housing, a lever arranged in said housing and in operative engagement with the ends of said ring, the latter being offset relative to each other to form cooperating oppositely disposed fulcrums for actuating said lever in one direction, a coiled spring for moving said lever in opposite direction, a link pivotally connected at one end to said lever and provided with lateral ears spaced from said lever and arranged to each side of the pivotal connection of said lever and said link, a screw adjustably seated in each lug and bearing against said lever, said screws being adjustable to vary the relative positions of said link and said lever with respect to each other and render said lever operable at different temperatures, and a switch mechanism operated by the opposite end of said link.
5. A thermostatic device comprising in combination a housing of metal having a high coefficient of expansion, said housing being provided with an integral circular wall, a resilient split ring arranged within said housing and bearing against the inner face of said wall, said ring having a comparatively low coefficient of expansion whereby the ends of said ring are caused to move relative to each other in accordance with the
- expansion and contraction of said housing, a lever loosely arranged in said housing and in operative engagement with the ends of said ring, the latter being offset relative to each other to form cooperating oppositely disposed fulcrums for said lever, a contact arm pivotally mounted in said housing, a link connected to said lever and extending at an angle therefrom, means for fixedly adjusting the position of said lever with respect to said link, thereby rendering the latter responsive to different temperatures, and a member operatively connected to said link and having lost motion operative connection with said contact arm.
6. A thermostatic device comprising in combination, a housing of metal having a high coefficient of expansion, said housing being provided with an integral circular wall, a resilient split ring arranged within said housing and bearing against the inner face of said wall, said ring having a comparatively low coefficient of expansion whereby the ends of said ring are caused to move relative to each other in accordance with the expansion and contraction of said housing, a lever loosely arranged in said housing and in operative engagement with the ends of said ring, the latter being offset relative to each other to form cooperating oppositely disposed fulcrums for actuating said lever, stationary contact member, a contact arm pivotally mounted in said housing and movable into and out of engagement with said stationary contact member, a link connected at one end to said lever, means for interengaging said lever and said link to adjust said lever and render it operable at different temperatures, a stationary mark indicia member cooperating with the free end of said lever to indicate the extent of adjustment thereof, a member operatively connected to the opposite end of said link and having lost motion operative connection with said contact arm, and a tension member connected to said contact arm for importing snap action thereto.

In testimony whereof I hereunto affix my signature this 22nd day of April, 1925.

JOHN O. CARREY.
